UNITED STATES PATENT OFFICE.

JOHN P. WILLIAMS, OF NEW YORK, N. Y.

ELECTRIC PROTECTION SYSTEM.

Application filed May 21, 1921. Serial No. 471,444.

To all whom it may concern:

Be it known that I, JOHN P. WILLIAMS, a citizen of the United States, and resident of New York, in county and State of New York, have invented certain new and useful Improvements in Electric Protection Systems, of which the following is a specification.

This invention relates to electric protection systems, and has special relation to an improved "static" system of protection for effecting, through operation of a high-tension spark coil or transformer, a "stunning" blow or shock upon a person attacking the system.

Heretofore it has been generally customary, in connection with electric protection for banks, jewelers, and analogous services, to depend upon the sounding of an alarm or a signal suitably located to notify the desired authorities of an attack upon the system. Such alarm systems, as now usually employed, are not operative to shock or stun a burglar or attacking person, and the alarm signals not only frequently operate falsely through defective conditions but their operation may be defeated by cutting of wires and other methods of burglarous attack without liability to personal injury from the circuits of the system.

While my improved static system of electric protection may be employed in connection with all systems employing alarm signals, as a supplementary protective feature, the improved system is operative to eliminate dependence upon an alarm signal in case of attack and serves to give a stunning blow or shock by electrical force to a burglar or attacking person the instant his hands are placed in contact with the protected structure.

In carrying out the operative purpose just stated, the conditions of the improved system are such that when the attacking person places his hands in contact with the protected structure, or otherwise contacts with the conducting structure, he makes contact in a circuit through the secondary of a high-tension electric spark coil which is so wound that an extremely high voltage (to a maximum of many thousands of volts, as desired) can be secured at the secondary through induction from the primary coil, thus producing a very severe shock the strength of

which can be made as great as required under the desired conditions and sufficient to stun the attacking person into insensibility. The usual alarm signal auxiliary can also be employed in the system, if desired, to operate simultaneously with the short circuiting of the secondary coil of the high-tension shock element.

My improved system is adapted to a wide range of application and use, for protection of bank vaults, safes, bank counter grille-work, prison cells, and in fact any service where electric protection of a structure or apparatus or device is desired, such as entrances to office buildings or private houses, the protection of automobiles against thievery, etc., and the improved static system can also be applied as a supplement to protective electric systems of the alarm signal type which are already installed and in service.

In the drawings, I have illustrated diagrammatically the wiring of the improved system, and its primary control apparatus, in its relation to several of the various conditions of service connection for which it is adapted.

Referring to the drawings, X designates a high-tension spark coil, which is made up of a primary and a secondary coil, p and s, wound around an iron core, A. A source of electrical energy, as a battery, designated at B, is in connection with the primary coil of the sparkler through an "interrupter," Y, embodying an armature, D, mounted on a spring contact, d, operative with relation to an adjustable contact, y, and in conjunction with the contacts d and y there is employed a condenser, as at Z, for governing the amount of the spark through the "interrupter." The primary is usually wound with a few layers of cotton-insulated wire wound over the core and preferably of No. 18 B. and S. gauge, and the secondary consists of several thousand turns of properly insulated wire wound over the primary. In operation, every time the "interrupter" shuts off the battery current in the primary there are currents induced in the secondary which cause sufficiently high voltage to span or jump across a space, and if contact is made by a person a shock of desired intensity is given; and when the current is sent through the primary, with the "interrupter" Y properly adjusted as to contact, the "inter-

rupter" instantly commences to operate and a spark will jump between the secondary wires.

In one operative service under the conditions of my improved static system, there is mounted within a protected vault the spark coil X, the battery B, an electric clock (of any usual construction) C, and all the wiring in connection with the primary coil of the sparker. A relay, as at E, for causing actuation of a "continuous" signal or alarm may also be mounted in circuit. The wiring in connection with the secondary coil of the sparker is connected to binding posts, F—G, which are also inside the vault. The purpose in placing the foregoing instruments and control circuits inside the vault is to protect them against tampering by any unauthorized person, but if it is desired to locate them outside the vault, as, for instance, in a desired room, they can be placed in a protected casing electrically lined and made sound proof to reduce the sound of the "buzz" of the spark coil.

From the binding posts F—G (inside the vault, as above described), which provide the circuit connection with the secondary coil s of the spark plug, extend wires, f—g, one of which f is grounded to a metallic part of the protected structure (such as the steel door or steel linings of the vault, as herein indicated) either inside or outside thereof, the other wire g being connected to an insulated portion of the protected structure at the outside thereof (such as an outside steel plate of the vault wall, as indicated at I, or an insulated steel floor plate surrounding the vault or suitably located, as indicated at J). One side of the secondary coil is thus grounded through a part of the protected structure which must be touched by an attacking person, and the other side is connected to an insulated part of the protected structure which must be stood upon or contacted with by the attacking person.

An auxiliary bell or signal attachment may, if desired, be interposed in the circuit of the wires f—g, by a relay, as shown at H, constituting controlling means and wired in series with one side of the secondary coil s by connection with the wire g, the relay having its contacts, 32—33, normally open, so that if the secondary wires are short circuited a current is sent through the relay and attracts its armature, 34, against its core, 35, thereby closing contacts 32—33 and actuating the alarm bell or signal, 31, in the circuit through connecting wires, 37 and 38, and a battery, 36. Such an auxiliary signal circuit can be employed in service or not, as desired, and various other auxiliary attachments may be suitably placed in circuit connection with the system.

I have also indicated, in the diagrammatic illustration, an auxiliary circuit con-

nection with the insulated wires, L, which are usually contained in a metal line conduit or cable casing, as at M, in burglar alarm systems as now generally employed, it being understood that in such alarm or signal systems the wires L, and also the conduit casing M if desired, are included in the general protective circuits which guard the protected structure and actuate an alarm, and are employed for carrying the wires thereof to an outside alarm or signal station. In this connection, the wire g of the secondary circuit f—g is connected by a wire, z, with the cable wires L, and the metallic conduit M is grounded through a wire, m, to the grounded wire f of the other side of said secondary circuit, and thus an attack upon the cable and conduit by cutting or otherwise causing closing of the secondary circuit will cause the desired shock action.

I have also illustrated a circuit connection with the metallic grille-work of a bank or protected structure, in which the grille-work, as at W, is grounded by connection, as by a wire, w, with the grounded side f of the secondary circuit f—g, and an insulated floor plate J or part which must be stood upon or contacted with by an attacking person is connected, as by a wire, x, with the other side g of said secondary circuit.

It will be understood that the grounded side f of the secondary circuit f—g is grounded through any suitable or adapted metallic part of the structure to be protected, as variously indicated at N in the diagrammatic illustration of the drawings.

In the system as above set forth, operation may be effected under the action of controlling means for divers conditions, for instance through the electrical circuit clock C in series with a switch, as at S, across contact posts, as at 1—3, or with the clock cut out and through a direct circuit across contact posts, as at 3—2, controlled by the switch S.

In operation with the clock C, the circuit is established from the positive side of the battery B through a wire, 39, to a contact post, o, in connection with one end of the primary coil p, through said primary coil and through the "interrupter" Y to a binding post, P, and through a wire, R, leading therefrom to an insulated key-switch, T (which switch may be located on the outside of the vault or protected structure, for reserve purposes), through said switch and a wire, v, to the frame of the clock C and through the clock contacts and hand, h, and a wire, 40, to the contact post 1 of the switch S, across the switch to the contact post 3, and through a wire, v¹, to the negative side of the battery B. The foregoing arrangement of wires or conductors and mechanism will cause operation of the spark coil X,

producing the desired high voltage in the secondary *s*, and establishing the system in status for operation, to shock or stun an attacking person, across the grounded side 5 *f* of the secondary circuit *f*—*g* and the insulated parts of the protected structure which are in connection with the other side *g*.

The employment of the clock-control *C* is for the purpose of enabling the throwing of 10 the system on and off automatically through the contact mechanism of the clock, which can be of the usual twenty-four, forty-eight or seventy-two hour construction, under which protection will be afforded continuously during the desired periods. For instance, the clock-control may be adapted to throw the system on automatically at night at a predetermined hour and off at a predetermined hour in the morning, when access to the vault or protected structure was 20 desired.

The insulated key-switch *T* is employed, in series with the clock circuit, so that in the event that the clock circuit should fail to 25 throw the system off an authorized person can by opening the switch release the spark coil from operation. For this purpose, said switch is preferably located in a secret or protected place external of vault or protected structure.

A signal lamp, *W*¹, may also be interposed in circuit, between the positive side of battery *B* and the control-clock *C* and under such conditions that when the electric current is passing through the clock-control a circuit through the lamp will be completed through a wire, 4, connected with the wire 39 from battery *B*, through a fuse, 5, in said conductor 4, through the lamp, and through 40 a wire, 6, connected with the wire *R* which leads to the clock-control. Thus, the signal lamp *W*¹ will be operating when current is passing through the clock-control, indicating that the system is "on." Said lamp signal is suitably located at a point external of the protected structure, and the fuse 5 is interposed in the lamp circuit for the purpose of precluding an attack thereon by sending an outside current through the lamp 45 and causing interference with the protective system or burning out of the spark coil.

In practical operation, with the system under the conditions of an auxiliary guard circuit as above described, when the clock-control *C* throws the system "off" (for instance, in the morning under bank customs) the authorized operator can then enter the vault or protected structure, and the switch *S* is set across its contact posts 2—3. This 50 cuts out the clock-control circuit and throws the control of the primary coil *p* through battery *B* for operation independent of the control-clock mechanism. The system is then operative as, for instance, a 55 "daylight" protection in bank installation

in connection with the grille-work *W* which is in the secondary circuit *f*—*g*, being grounded through connection with the side *f* thereof and having the insulated contact plate *J* connected with the other side *g*.

Auxiliary to such grille-work protection, there are employed separate hand or foot contacts suitably located back of the grille and operable by the official at the grille. Such contacts are in normally open position, as indicated at 7—8, with a wire, 10, extending from contact 7 to a wire, 48, to the positive side of the battery *B*, and a wire, 11, extending from contact 8 to the wire *v*¹ to the negative side of the battery. Under the operative conditions of the structural arrangement just described, if an attacking person stands upon the insulated plate *J* in front of the grille and touches his hand to the grounded parts of the grille, the operator, by simply closing the contacts 7—8, establishes a circuit from the positive side of battery *B* through wire 39, the primary coil, and the connection to wire 10, across the contacts, and through wire 11 back to the negative side of the battery, thus closing the circuit through the primary *p* of the spark coil and causing the system to operate to give a shock across the plate *J* and grille *W*. In the conditions as just set forth, the system will be operative only so long as the operator retains the normally-open contacts 7—8 closed.

If, however, it is desired, by closing contacts 7—8 or other suitably located similar normally-open contacts, as indicated at 12—13, to effect continuous service of the system by mere instant closing of said contacts without retaining them closed, a circuit arrangement is provided as follows: 100 from the positive side of battery *B* through wire 9 and through a wire, 14, across the contacts as at 12—13, and through a wire, 15, to the coil of the relay *E*, and contact spring 47, armature plate 18, through the frame, 16, of the relay, and through a wire, 17, extending therefrom to the switch-contact 2, across the switch contacts 2—3, and back to the negative side of the battery through wire *v*¹. This magnetizes the relay 105 *E* and releases its armature plate, 18, which closes the circuit across normally-open contacts, as at 19—20, and the current is then directed in continuous service through the primary coil *p* of the spark coil as follows: 110 from the positive side of battery *B* through wire 39 to one side of the primary coil, and from the negative side of the battery through wire *v*¹, switch-contacts 2—3, wire 17, the frame 16 and armature 18 of the relay *E*, and through contact 20, wire 21, wire 115 *R*, and "interrupter" *Y* to the other side of the primary coil *p*.

As an adjunct in the operation of the relay *E*, an auxiliary bell or signal may be

thrown into continuous service when the source under the control of the guard circuit, and means for protecting said transformer and said connection and the source of current.

5. In an electrical protection system, a conducting structure to be guarded, means for generating high potential current, having a connection from its positive and negative poles respectively to parts of said structure which are adapted to be bridged by an attacking person, controlling means for said generating means, and means for protecting said generating and controlling means and said connection.

6. In an electrical protection system, a conducting structure to be guarded, a transformer for generating high potential current, having a connection from its high-potential poles respectively to parts of said structure which are adapted to be bridged by an attacking person, controlling means for said generating means, and means for protecting said generating and controlling means and said connection.

7. In an electrical protection system, a conducting structure to be guarded, a transformer for generating high potential current, having a connection from its high-potential poles respectively to parts of said structure which are adapted to be bridged by an attacking person, controlling means for said generating means, and means for protecting said generating and controlling means and said connection.

8. In an electrical protection system, a conducting structure to be guarded, means for generating high potential current, having a connection from at least one pole to the structure to be guarded, an auxiliary signal circuit having controlling means in said connection, controlling means for said generating means, and means for protecting said generating and controlling means and said connection.

9. Having thus described my invention, I claim and desire to secure by Letters Patent:

1. In an electrical protection system, a conducting structure to be guarded, means for generating high potential current, having a connection from at least one pole to the structure to be guarded, controlling means for said generating means, and means for protecting said generating and controlling means and said connection.

10. 2. In an electrical protection system, a conducting structure to be guarded, a transformer for generating high potential current, having a connection from at least one high-potential pole to the structure to be guarded, an auxiliary guard circuit for said structure, said guard circuit including circuit-changing means and a source of current and switching means for including the primary of said transformer and said source of current in circuit for continuous operation or for including said primary and said source under the control of the guard circuit, and means for protecting said transformer and said connection and the source of current.

11. In testimony whereof I have signed the foregoing specifications.

JOHN P. WILLIAMS.
